TIMER FOR LEER LOADERS

Arthur W. Beeson, Washington, Pa., assignor to
Hazel-Atlas Glass Co., Wheeling, W. Va., a corporation of West Virginia

Application February 12, 1932, Serial No. 592,623

9 Claims. (Cl. 74—169)

This invention relates to leer loaders for glassware and has for its primary object to provide a simple yet efficient timing device for the operation of the pusher bar for projecting the ware 5 into the leer.

The number of pieces of ware to be carried into a particular annealing leer at each operation of the pusher bar depends to a large extent on the horizontal dimensions of the ware, and the present invention comprises a very simple timing mechanism which may be associated with any type of leer loader and which will time the operation of the loader in accordance with the number of pieces of ware made on the forming machine.

A further object of the invention consists in a timing device which by the mere raising or lowering of a calibrated rod will cause a leer loader to operate after the formation of any selected number of pieces of ware.

Other objects and advantages of the invention will be apparent from the following description when taken in connection with the accompanying drawings, in which,

25 Figure 1 is a fragmentary side elevational view of a leer and leer loader with the novel timing device connected therewith.

Figure 2 is an enlarged perspective view of the timing mechanism.

30 Figure 3 is an end view of the timer, showing in dotted lines the position of the parts when releasing the motor for operation, and,

Figure 4 is a horizontal sectional view taken on line 4—4 of Figure 2.

35 Referring to the drawings in more detail, the numeral 1 indicates generally a leer for annealing glassware, only the forward portion of the leer in which the glass enters being shown. Mounted on top of the leer is a base plate 2 for supporting

40 a leer loader of the pusher bar type. The present invention is in no manner limited to use with a certain type of leer loader, but for purposes of illustration there is shown the leer loader disclosed in the patent to Covey No. 1,839,375, granted January 5, 1932.

45 While the leer loader per se forms no part of the present invention a brief description of its construction will be made in order to fully disclose the purpose and function of the timing device to which the present application is directed.

Pivotedly mounted on a bracket 3 secured to the base plate 2 is a frame 4. This frame is provided with pairs of rollers 5 in which is slidably mounted a rod 6. This rod has pivotally secured at its

outer end a depending arm 7 on the lower end of which is secured a pusher bar 8.

Adjustably mounted on the rod 6 is a link 9 which has its opposite end pivotally connected to a crank arm 10 journaled in a bracket 11 mounted on the base plate 2. This crank arm is driven by a sprocket chain 12 to which power is transmitted by a sprocket wheel 13 driven from a motor 14 (Figure 2).

As will be readily understood, all of the ware 10 to be projected into the leer in a particular movement of the pusher bar is not always placed directly in alignment therewith. For this reason a side pusher bar 15 is provided. This bar 15 is pivotally connected to the upper end of a link 16 15 which has its lower end pivoted to the side of the leer. A crank 17 is journaled to the side of the leer as indicated by the numeral 18 and has one of its arms pivotally connected to the auxiliary pusher bar 15. A link 19 is journaled to the other 20 arm of the crank 17 and has its opposite end connected to a bell crank lever 20 pivoted on the upper forward end of the leer 1 as indicated by numeral 21. A link 22 connects this bell crank to the rocking frame 4 heretofore mentioned. It 25 will be understood, therefore, that between the several reciprocations of the pusher bar 8 toward and from the leer, the auxiliary pusher bar will be operated through the motion of the frame 4 to project any improperly placed ware into the 30 path of the pusher bar.

In order to raise the pusher bar 8 after it has drawn a line of ware into the leer, an arm 23 provided with a roller 24 is mounted on the shaft carrying the crank 10. As the crank 10 moves in a clockwise direction to pull the pusher bar 8 toward the mouth of the leer, the rod 6 is of course drawn to the right (Figure 1) and the roller 24 is arranged to contact the free end of the rod 6 and depress it thereby raising the pusher bar just as it reaches its innermost position. Continued movement of the crank arm 10 and the arm 23 lifts the roller 24 from the rod 6 and thus allows the rod and carriage 4 to return to normal horizontal position and brings the pusher bar 8 into 45 position for projecting another line of ware into the leer.

In the raising and lowering of the pusher bar in this type of leer loader, it is desirable that the bar be raised in as nearly a vertical plane as possible so as to avoid interference with other ware being brought forward to be carried into the leer on the next operation of the pusher bar. To this end the arm 7 on which the pusher bar is mounted is provided with an extension 25 above its pivotal 55

point with the rod 6. Pivot to this extension of the rod 7 as indicated at 26 is an arm 27 which has its other end slidably mounted between rollers 28 supported on a bracket 29 secured to the rocking frame 4. This end of the arm 27 is provided with a roller 30 adapted to be engaged by a cam 31 fixed on the same shaft which carries the crank arm 10 and the arm 23, but arranged at an angle of about ninety degrees therewith. The chain 12 therefore drives not only the crank 10, but also the arm 23 and the cam 31, and the positions of these parts are such that after the pusher bar has completed its inward movement to push the ware into the leer and starts back again, the cam 31 will engage the roller 30 giving a quick forward motion to the arm 27 and thus rocking the arm 7 about its pivot with the rod 6. This combined movement, namely, the rocking upwardly of the arm 7 through the depression of the carriage 4 and the rocking of the arm 7 about its pivot by engagement of the cam 31 with the roller 30, will cause the pusher bar to be raised initially in a substantially vertical plane thereby avoiding any tendency to knock over ware being brought into position to be subsequently operated upon by the pusher bar. A spring 32 is connected to the rod 6 and the extension 25 of arm 7 so as to return the arm to substantially right angular relation to rod 6 after the cam 31 leaves the roller 30.

30 The cam shaft of a conventional forming machine is indicated by the numeral 33 and is provided with a gear 34 meshing with a gear 35 on a vertical shaft 36. This shaft has fixedly secured thereto, a cam 37 for cooperation with cam rollers 38 on a lever 39. A plate 40 provides the support for the lever 39 on which it is pivoted as by means of a bracket 41, and the plate is in turn supported on a base plate 42. Plate 40 is circumferentially adjustable on the base plate 42 and may be secured in any adjusted position by means of a clamp 43.

Also mounted on plate 40 is an air valve 44 of the piston and cylinder type, and provided with a piston rod 45 connected to the lever 39. 45 Air under pressure is supplied to the valve 44 by conduit 46, and conduits 47 and 48 lead from the valve to opposite ends of an air cylinder 49. This cylinder is more clearly disclosed in Figure 2 of the drawings and will be described more in detail in connection with the description of the timing mechanism.

50 The timing mechanism which serves to regulate the interval of time between the reciprocations of the pusher bar 8 so that 2, 3, 4 or any desired number of pieces of ware may be formed on the forming machine and brought in front of the pusher bar between its cycles of operation, will now be described.

Associated with the motor 14 is a gear box 50, and keyed to the shaft thereof is a gear wheel 51. The sprocket wheel 13 which drives the chain 12 is loosely mounted on the shaft of gear wheel 51, and its hub 52 has pivoted thereon a pawl or clutch member 53 provided with a pin 54. The pawl serves as a clutch for connecting the continuously rotating gear wheel 51 with the sprocket wheel 13, and a spring 55 is adapted to force the tooth of the pawl into engagement with the teeth of the gear wheel.

70 After the sprocket wheel 13 has made a complete revolution it is thrown out of gear with the motor by means of an arm 56 pivoted to a base plate as indicated by numeral 57. This arm is forked at its upper end, one of the prongs of the

fork being indicated by the numeral 58 and having its free end positioned inwardly of the pin 54 on pawl 53. It will be understood therefore that when the arm 56 is in operative position, the pin 54 will ride up onto the arcuate prong 58 and withdraw the tooth of the pawl from engagement with the teeth of the gear wheel as indicated in Figure 2. It will also be noted that this construction provides a positive means for withdrawing the clutch and positively maintaining it in inoperative position, so that there is no possibility of the clutch becoming worn by riding against the teeth of the gear.

10 The other prong 59 of the arm 56 is connected with a link 60 which is in turn connected with a bell crank lever 61 pivoted to a bracket 62 on the main frame of the timing mechanism. A spring 63 having its ends fastened to the gear box and to the arm 56, serves to return the arm to operative position after each release of the pin 54.

15 The main frame of the timing device is indicated by the numeral 64, and mounted therein for vertical adjustment is a rod 65. The rod 65 is provided with an angular projection 66 on its lower end, and is, therefore, substantially L-shaped in design. The rear edge of this L-shaped member is provided with a plurality of ratchet teeth 67, and a spring pressed pawl 68 pivoted to the frame 64 serves to hold this L-shaped member 20 in various vertically adjusted positions. Slidably mounted in the frame 64 is a ratchet bar 69 normally supported at its lower end by the angular extension 66 of the L-shaped member 65. It will be apparent, therefore, that the lower limit 35 of movement of the ratchet bar 69 will depend entirely upon the vertical position of the L-shaped member 65.

25 The ratchet bar 69 is adapted to be vertically raised in a step-by-step movement by means of 40 pawls 70 and 71. The pawl 70 is pivotally mounted on a plate 72 which is in turn connected to the piston rod of cylinder 49 and hence the pawl is raised when air is admitted to the lower end of the cylinder. The pawl 71 also coacts with 45 the teeth of the ratchet bar 69 and serves to lock the bar after each upward movement thereof by the pawl 70.

30 This step-by-step movement of the ratchet bar 69 continues until such time as the upper end of the ratchet bar engages the overhanging portion 73 of a plate 74. The last step of the ratchet bar raises this plate 74 and its over-hanging portion 73, which it will be noted is in contact with the horizontal arm of the bell crank lever 61. This movement rocks the bell crank lever about its pivot and thus through the medium of link 60 withdraws the arm 56 from the pin 54, thereby permitting the pawl to engage the continuously rotating gear wheel 51 and cause sprocket wheel 60 13 to drive the chain 12, thereby setting the leer loader in operation.

35 It will be remembered that the valve for admitting air to the opposite ends of the cylinder 49 is connected with the valve shaft of the forming machine and these parts are so designed that the pawl 70 is caused to reciprocate once for each article formed on the forming machine.

40 It will be apparent, therefore, that the vertical adjustment of the L-shaped member 65 which 70 determines the lower limit of the ratchet bar 69, will determine the number of articles which are projected into the leer at each operation of the leer loader, and it will be noted that indicia 75 on the upper end of the L-shaped member per-

mits a ready adjustment of the member in accordance with the number of articles to be projected into the leer in each operation.

It is essential, of course, after the plate 74 is raised to rock the bell crank lever 61 so as to set the leer loader in operation, that it be released so as to allow the resetting of the arm 56 to again disengage the pawl after one cycle of operation of the leer loader. Nevertheless, the bell crank 10 must not be released so rapidly as to permit the spring 63 to return the arm 56 to operative position before the pawl has actually moved into its operative position in engagement with the gear wheel. To this end the plate 74 is provided with 15 cams or offset portions 76 which are normally seated in correspondingly shaped recesses 77 provided in a plate 78 which forms a part of the frame of the timing device. Pivoted to the lower end of the plate 74, as indicated by numeral 79, 20 is a plate 80 which has its upper end extending into a beveled slot 71 formed in cross bar 82 of the frame structure. As the plate 74 is raised by the last upward step of the ratchet bar, it is cammed slightly to the right thereby rocking the shorter plate 80 in a counter-clockwise direction about its pivot 79. The lower end of the plate 80 is thus disposed over the pawl 70 which is in raised position at this particular moment, whereby the pawl temporarily supports the plate 74 25 to hold the arm 56 in releasing position. This lateral movement of the plate 74 also serves to move the pawls 70 and 71 out of engagement with the ratchet bar 69, thereby allowing the latter to drop to its lowermost position where it 30 is supported on the angular extension 66 of the L-shaped member 65. When air is again admitted to the upper end of the cylinder 49 to retract the pawl 70, the latter will, of course, disengage the projecting end of the plate 80 and 35 the parts will return to normal position as indicated in Figure 2.

The operation of the device has been fully described in connection with the description of the details of construction and need only be briefly 40 repeated. The phase of operation between the forming machine and the pusher bar may be adjusted by a suitable adjustment of the plate 40 with respect to the plate 42, as this permits a relative movement between the cam of the forming machine and the cam rollers of the lever 39 which operates the valve 44 for controlling the 45 operations of the cylinder 49. The timing of the operation of the pusher bar with respect to the number of articles formed on the forming machine is controlled entirely by the vertical position of the L-shaped arm 65 inasmuch as this member controls the lower or initial position of the ratchet bar 69 and thus determines the number of upward impulses which must be applied 50 to the ratchet bar before the same will cause the bell crank lever 61 to be operated to disengage the pawl 53. The release of the pawl 53 allows the same to engage the gear wheel 51 which is continuously operating and which will, 55 therefore, cause the sprocket wheel 13 to make a complete revolution and thus rotate the crank arm 10 to cause a complete cycle of operations of the leer loader. After the gear wheel 51 has made a complete revolution, the pawl is automatically disengaged therefrom by the arcuate prong 52 of the arm 56. The too rapid springing back of the arm 56, after it has been released from the pawl by the upward movement of the ratchet bar 69, is prevented by the plate 74 which 60 is temporarily supported in its uppermost posi-

tion by reason of the lower end of the plate 80 engaging the pawl 70; the plate 80 being canted into operative position by reason of the lateral movement of the plate 74 which is caused by the action of the cams 76 riding over the cam surfaces 77 of the plate 78. These parts are returned to the normal position just as soon as air is supplied to the upper end of the cylinder 49 to bring the pawl 70 to its lowered position.

From the foregoing description taken in connection with the accompanying drawings, it will be seen that I have provided a rather simple construction of timing device for leer loaders and similar apparatus; that it may be readily installed on any such devices regardless of their particular 10 construction; that means is provided for adjusting the timing device to cause the leer loader to operate after any desired number of articles have been formed; and that this adjustment may be accomplished by merely adjusting a bar which 15 is provided with suitable indicia to determine the 20 desired position thereof.

In accordance with the patent statutes, I have described what I now believe to be the preferred form of construction but it is to be understood 25 that various changes and modifications may be made without departing from the spirit of the invention, and all such changes and modifications are intended to be included within the scope of the appended claims. Moreover, the term 30 "clutch" as used in the claims is intended to include any device for setting in operation the driving mechanism for the leer loader.

What I claim is:

1. A timing device for operating a clutch for 35 leer loaders including a vertically movable member for rendering the clutch operative; a bar movable vertically step-by-step to engage and elevate said member, means operated by the movement of said member for resetting the bar by 40 gravity, means maintaining said member in its elevated position while the bar is being reset, and means for subsequently dropping said member.

2. A timing device for operating a clutch for 45 leer loaders including means for rendering the clutch operative; said means including a ratchet bar, a cooperating pawl for imparting a step-by-step movement to the bar, a member on which 50 said bar is supported, and a pawl and ratchet for supporting said member in various adjusted positions.

3. A timing device for operating a clutch for 55 leer loaders including means for rendering the clutch operative, said means including a vertically disposed ratchet bar, a cooperating pawl for imparting a step-by-step movement to the bar, an L-shaped member on which said bar is 60 slidably supported, and a pawl and ratchet for supporting said member in various adjusted positions.

4. A timing device for operating a clutch for 65 leer loaders including means for rendering the clutch operative, said means including a movably mounted plate and a ratchet bar associated therewith, a pawl cooperating with the ratchet bar for imparting a step-by-step movement thereto, said bar engaging and moving the plate to render the clutch operative, means for moving the plate laterally to release the pawl, and means for maintaining the plate in clutch-releasing position for an appreciable period of time.

5. A timing device for operating a clutch for 70 leer loaders including means for rendering the clutch operative, said means including a movably mounted plate and a reciprocably mounted 75

- ratchet bar associated therewith, a pawl engaging the ratchet bar for imparting a step-by-step movement thereto, said bar engaging and moving the plate to render the clutch operative, 5 means for moving the plate laterally to release the pawl, means for varying one limit of movement of the bar, and means for maintaining the plate in clutch-releasing position for an appreciable period of time.
- 10 6. In a timing device a vertically movable plate, a ratchet bar adapted to raise said plate, a co-operating pawl for imparting movement to the ratchet bar, and a cam cooperating with the plate for biasing said plate laterally to disengage 15 said pawl from the ratchet bar.
7. In a timing device a vertically movable plate, a ratchet bar adapted to raise said plate, a co-operating pawl for imparting movement to the ratchet bar, a cam cooperating with the plate 20 for biasing the plate laterally to disengage said pawl from the ratchet bar, and a pivoted arm carried by said plate and adapted to engage said
- pawl to momentarily support the plate after the ratchet bar has been released.
8. In a timing device a vertically movable plate, a ratchet bar adapted to raise said plate, a pawl for imparting a step-by-step movement to the ratchet bar, an adjustably mounted support for the ratchet bar, and a cam cooperating with the plate for biasing the plate laterally to disengage the pawl from the ratchet bar.
9. In a timing device a vertically movable plate, 10 a ratchet bar adapted to raise said plate, a co-operating pawl for imparting a step-by-step movement to the ratchet bar, an adjustably mounted support for the ratchet bar, a cam co-operating with the plate for biasing the plate 15 laterally to disengage the pawl from the ratchet bar, and a pivoted arm carried by said plate and adapted to engage said pawl to momentarily support the plate after the ratchet bar has been released.

ARTHUR W. BEESON.
